UNITED STATES PATENT OFFICE.

LUCIEN I. YEOMANS, OF CHICAGO, ILLINOIS, ASSIGNOR TO A. O. SMITH CORPORATION, OF MILWAUKEE, WISCONSIN, A CORPORATION OF NEW YORK.

CENTRIFUGAL CASTING MACHINE.

Application filed November 1, 1924. Serial No. 747,142.

The invention relates to machines designed for use in casting tubular articles by the centrifugal process.

It is embodied in a structure in which the 5 rotating mold is provided with adjunctive devices by which a trough containing a measured quantity of molten metal may be inserted in the mold and partially rotated so as to permit the molten metal to be 10 dumped therefrom and flow evenly over the edge of the trough so as to be evenly distributed over the surface of the mold, with means for supporting the trough in proper position while being introduced into and 15 withdrawn from the mold, and during the dumping operation.

The invention further resides in the positioning within the mold of a stationary track or raceway over which the trough may 20 be moved.

The invention also comprises means for withdrawing the casting from the mold, such means residing in a truck or carrier operating over the stationary track or race- 25 way before mentioned, whereby when the casting has set at a suitable temperature it may be withdrawn from the mold preparatory to another casting operation. The carrier for withdrawing the casting is provided 30 with means for engaging the casting at its upper side so as to free its lower side from engagement with the mold, and so facilitate its removal from the mold.

The invention further resides in means 35 for supporting the said track or race-way at one end so that the casting may be withdrawn without disturbing the position or relative location of the track, this being effected by withdrawing part of the supports 40 at one time to permit movement of the casting, then restoring to position the support previously withdrawn, and then withdrawing the other support to permit the clear and unobstructed movement of the casting 45 over the track or race-way, and away from the casting machine.

The features of novelty residing in the invention will now be pointed out in connection with the accompanying drawings, 50 and then set forth in the appended claims.

In the drawings:

Figure 1 is a vertical sectional view longitudinally of my improved machine.

Fig. 2 is a transverse sectional view on

the line 2—2, Fig. 1, looking in the direction of the arrows.

Fig. 3 is a view in elevation of one of the supports for the track or race-way over which the pouring trough and the truck or carrier move, looking from the right of Fig. 1.

In the drawings, the numerals 10 and 11 indicate stands provided with large openings through which the rotatable mold 12 may be passed, one stand being located near each end of the mold. Supporting rollers 13 and 14 are journaled in the lower part of each of the stands at opposite sides thereof and in separated positions to receive the mold which is supported thereon. A third 70 roller 15 is journaled in a floating bearing at the top of each stand, and is caused to engage the periphery of the mold by means of expansion springs 16, which are adjustable as to their pressure upon the journals 75 of the roll 15 by means of screws 17. The cap or dam 18 upon one end of the mold is provided with a pulley 19, by means of which a driving belt may be utilized for imparting a movement of rapid rotation to the 80 mold during the casting operation. The cap or dam 20 at the other end of the mold is held in position by means of outwardly driven radial keys 21, which engage in eyes 85 formed in projection extending from the mold, or by any other suitable means, the construction being such that the cap or dam 20 may be removed from its closing position in an expeditious manner.

Secured in position between the stands 10 and 11 is a stand 22 in which are journaled guiding rollers 23 and 24, which receive between them a circumferential rib 25 placed about the exterior of the mold, and through this construction the mold is held from longitudinal movement. The parts thus far described may be of ordinary construction.

Adjacent the driven end of the mold, is a stand 26 provided with a bracket 27 upon which rests one end of a track or race-way 100 28 passed through the tubular mold and the ring-like caps thereon. This track 28 may be substantially in the form of an I-beam. A pair of brackets 29, one of which is shown in Fig. 1, is attached to opposite sides of the track 28 about mid-way of its length, and another pair of similarly arranged brackets 31 and 32 is attached to the other 105

end of the track, the pairs of brackets being separated from each other a distance which is a little greater than the length of the casting to be formed in the mold, this arrangement being for a purpose which presently will be described.

The brackets 29 rest upon the upper ends of vertically movable posts formed as screws 33, one of which is shown in Fig. 1, 10 and the brackets 31 and 32 in the same manner engage the ends of like screws 35 and 36, the screws being threaded into rotating nuts 37, which are supported upon stands 38, resting upon the floor.

15 The nuts 37 are formed circumferentially as worm gears 39, each pair of which is engaged by worms 40, upon a transverse shaft 41, which may be rotated to simultaneously raise and lower the screws of a pair into and out of engagement with the brackets upon the track 28. The pairs of screws are arranged for alternate operation, so that the track 28 is supported by not less than one pair of screws at all times.

20 Trolleys 42 and 43 operate over the lower flange of the track 28, and depend therefrom so as to support a pouring trough 44, which is journaled at its ends in the said trolleys, so that it may be partially rotated to empty 30 the molten metal therein into the mold, such metal flowing over the edge of the trough in a thin but wide stream, so that the fluid metal is evenly distributed over the surface of the mold. One of the journals of the 35 trough 44 is extended as at 45, and to the projecting end of the shaft thus formed, is affixed a hand wheel 46, or other device, for convenient operation in partially rotating the trough to empty its contents.

40 The trolley mounting for the pouring trough enables the latter to be freely moved along the track 28, both from the operative position shown as well as into its retracted position at the other end of the track. In 45 such retracted position, the trough is adapted to receive a measured charge of molten metal from the near-by furnace, and then moved along the track to its operative position within the mold, after which it may be 50 turned so that the molten metal will flow into the mold in the manner described. The mold is then rotated to form the casting.

55 After the casting has been made, it is withdrawn from the mold by a specially designed truck or carrier 47, which operates along the top flange of the track 28. The platform of the truck is equipped with casting supports 48 and 49, which normally lie 60 in a plane below that of the inner surface of the casting 50 at its upper side, so as to permit a free and unobstructed movement of the truck into the mold, and into a position where it may receive and support the 65 casting.

The casting supports 48 and 49 are provided with depending pins which are guided in the platform of the truck so as to permit vertical movement of the said supports. A small motor 51, mounted upon the truck, 70 rotates a screw shaft 52, threaded into wedges 53 and 54, which latter have a sliding movement longitudinally of the truck and in the spaces between the platform and the underside of the casting supports 48 and 49, so that as the wedges enter further into such spaces, the said supports 48 and 49 are raised into engagement with the interior surface of the casting. The shrinkage of the casting in cooling frees it from frictional 80 engagement with the surface of the mold, so that the casting may be easily withdrawn in the outward movement of the truck.

After the casting has been made and engaged by the truck, as a preliminary to its withdrawal from the mold, the near pair of screws 33 are run down to a lower position so that their upper ends will be below the path of movement of the casting, and thus permit the movement of the same out from 90 the mold. When the truck and the casting have been moved to the dotted line position shown in Fig. 1, the screws 33 are run up so as to engage the brackets 29 and support the track 28. The screws 35 and 36 are then withdrawn as before, so as to enable the casting 50 to be taken away from the machine, after which the said screws are restored to their supporting position with relation to the track 28. The operations described are repeated as successive castings are made.

Having thus described my invention, what I claim and desire to secure by Letters Patent of the United States, is:

1. In a centrifugal casting machine, a mold and means for rotating the same, a stationary track extending into the mold, and a truck movable over the track to engage the casting and withdraw it from the mold. 110

2. In a centrifugal casting machine, a mold and means for rotating the same, a track extending into the mold and having fixed support at one end and movable support at the other, whereby the casting may 115 be withdrawn from the mold without disturbing the arrangement of the said track, and a truck movable over the track for withdrawing the casting from the mold.

3. In a centrifugal casting machine, a mold and means for rotating the same, a track extending into the mold, and a truck operating along the track into and out of the mold and provided with means for engaging the casting, the said track having 125 fixed support at one end and movable support at the other, whereby the casting may move with the truck and be withdrawn from the casting machine without disturbing the arrangement of the said track. 130

4. In a centrifugal casting machine, a mold and means for rotating the same, a track extending into the mold, a truck operating over the track into and out of the mold and provided with means for engaging the casting, the said track having a fixed support at one end and a removable support at the other, the latter support comprising screw mechanism spaced apart a distance exceeding the length of the casting to permit movement of the truck with the casting, and means for withdrawing the screw mechanism in alternation to permit removal of the casting from the machine without disturbing the arrangement of the track.
5. In a centrifugal casting machine, a mold and means for rotating the same, a track extending into the mold, a truck operating thereover, and means on the truck engageable with the casting to withdraw the casting from the mold on the outward movement of the truck.
6. In a centrifugal casting machine, a mold and means for rotating the same, a track extending into the mold, a truck operating thereover and provided with means for engaging the casting, and means operating the said means into engagement with the casting to withdraw the latter from the mold in the outward movement of the truck.
7. In a centrifugal casting machine, a mold and means for rotating the same, a track extending into the mold, a truck operating thereover and provided with means for engaging the casting, and means on the truck for operating the said means radially into engagement with the casting to withdraw the latter from the mold in the outward movement of the truck.

In testimony whereof, I have signed my name at Milwaukee, this 27th day of October, 1924.

LUCIEN I. YEOMANS.
